UNITED STATES PATENT OFFICE.

EMIL R. JAHNA, OF PERRYSVILLE, INDIANA.

CONCRETE-ROOFING-TILE MACHINE.

Application filed May 9, 1922. Serial No. 559,551.

To all whom it may concern:

Be it known that I, EMIL R. JAHNA, a citizen of the United States, residing at Perrysville, county of Vermillion, and State of Indiana, have invented certain new and useful Improvements in Concrete-Roofing Tile Machines, of which the following is a specification.

One of the objects of this invention is to provide a machine for moulding roofing tile, capable of expeditious hand operation and in which the tile is formed fully complete and delivered on a pallet for drying and finishing operations.

15 A further object is in the improvement of constructive details, one being the provision of adjustable means for levelling the raised end edges of the tiles uniformly, another to furnish means for forming the corners of the 20 tiles interengagingly, and finally, to arrange the machine so that tiles of different conformation can be made therein.

These and other objects, which will appear as the description progresses, are attained 25 by the novel construction and combination of parts hereinafter described and shown in the accompanying drawings, forming a material part of this disclosure, and in which—

Figure 1 is a perspective view showing the 30 upper portion of a tile machine made in accordance with the invention.

Figure 2 is an enlarged plan view of the tamping bar as used in connection with the machine.

35 Figure 3 is a front elevational view of the same.

Figure 4 is a transverse sectional view showing the levelling bar and indicating the application of the machine.

40 Figure 5 is a plan view of the levelling bar.

Figure 6 is a fragmentary sectional view, taken on line 6—6 of Figure 5.

Figure 7 is a perspective view of one form of tile as made in the machine, showing the 45 joints between adjacent elements.

Figure 8 is an enlarged perspective view showing the removable block constituting the head of the mould.

50 Referring, particularly to Figure 7 of the drawings, the numeral 10 designates in general a series of roofing tiles, the same having curved longitudinal arches 11 raised from the general level 12, and along one of their lateral edges are raised ribs 13 having 55 between them a recess 14 adapted to engage a corresponding tenon 15, formed on the

under side of the edge of the adjacent tile, the arrangement being such as to prevent lateral separation.

These ribs, as shown, extend below the 60 next adjacent row of tiles, and raised transverse elements 16 are positioned below lugs (not shown) in the next upper tier of tile 65 engaging in such manner as to prevent separation of the tiles lengthwise.

At one end of the tile the ends of the ribs 13 are cut away, as at 17, and at the other end project into recesses 18, the walls 19 of which are engageable with corresponding recesses 20 formed in the outer sides of the 70 wall of the next adjacent tiles in their opposite edges.

These tiles are formed singly in suitable moulds on "pallets" disposed in the machine, which consist of paired legs 23 connected 75 at their ends by angle beams 24 and 24' and have bolted on their upper flanged faces cross bars 25.

The pallets, generally designated by the 80 numeral 26, rest on supports 27, in turn resting on adjusting screws 28 threaded into the cross bars 25 and are held in adjustment by check nuts 29.

A hollow rectangular box-like frame, comprised of vertical side plates 30 having 85 flanged feet 30', are bolted to the cross bars 25, the box having a rear end plate 31, shaped in conformity with the tile and a raised front plate 32, this box being receptive of the pallet. The plate 32 has a separable wear member 62 securely attached by screws 63 acting as dowels and passing through raised extensions 64 registering with lugs 65 formed with the plate 32, thus allowing replacement of 90 the part most subject to wear.

95 A pair of rails 42 are fastened by their flanged feet 42' to the bars 25, the rails extending longitudinally in parallel with the box sides 30 from which they are uniformly spaced.

In order to level the surfaces of the tile element 16 and maintain them at a uniform height, a levelling bar 33, having operating handles 34, is used.

This bar is also provided with adjusting 105 means consisting of blocks 35 adapted to rest on the rails 42, these blocks having lugs 36 which act as guides on the outer sides of the rails, as shown.

110 Fixed in these blocks are pins 37 slidably engaging in holes 38 in the bar 33, the blocks being adjusted by screws 39 threaded in the

bar and having collars 40 rotatable in openings formed in the lower sides of the blocks, these collars being held to the reduced cylindrical ends of the screws by screws 41 or 5 other analogous means as preferred.

Thus the distance of the bar 33 relative to the rails may be readily adjusted so that its shearing effect on the surfaces 16 may be maintained uniformly, should the rails 10 wear or for other purposes.

The tamping bar, generally designated by the numeral 45, is provided with handles 46, between which is a raised flange 47, the lower side of the bar being shaped to produce the upper surface of the tile as it is moved over it.

This bar is guided on the rails 42 by spaced lugs 48 and carries a projection 49 adapted to produce the recess 18 in the tile 20 corner, the recess 20 in the opposite corner of the tile being formed by a projection 50 formed with the front plate 32 of the box.

Also projecting from the plate 32 are stops 51 and 51' against which the bar 45 25 makes contact and by which the thickness of the tile element 16 is determined.

A pair of curved arms 52 are hingedly engaged to the rear of the structure and carry a shear frame 53 provided with a 30 handle 54, the side walls of this frame being in register with the side walls 30 of the mould, and acting cooperatively with them in finishing the sides of the tiles.

The wall of the frame adjacent the arms 35 has a block 55 which forms the tile recess 17, and is also provided with a block 56 to form the tile recess 20.

In operation, the pallet is placed in the mould or box and adjusted to produce the 40 desired thickness of the tile; the bars 33 and 45 are removed and the tile material in plastic form entered into the mould, whereupon the tamping bar 45 is placed upon the rails, at the rear end of the machine and 45 advanced by usual tamping and smoothing movements until it contacts with the stops 51 and 51', this bar producing the shape of the top of the tile.

When the bar 45 has performed its function, the surplus material will be at the 50 front, against the plate 32, the bar is then wholly removed or carried to the rear and

the smoothing bar 33 placed on the rails, moved to the front, shearing the surplus stock and determining the height of the tile 55 element 16.

The shearing frame is then pressed down over the mould containing the tile, defining its side edges and returned to the position shown.

The tile, together with its pallet, is then ready to be removed and another pallet substituted for subsequent operations.

Thus it will be seen that a complete and comprehensive machine has been disclosed for the purpose indicated, including an adjustable and effective means for determining the height of the tile elements 16 so that the same may be fully finished while in the machine.

As changes in construction could be made within the scope of the invention, it is intended that all matters contained in the foregoing description or shown in the accompanying drawings shall be interpreted 75 as illustrative and not in a limiting sense.

Having thus described my invention, what I claim as new and desire to secure by Letters Patent, is:—

1. A tile making machine comprising a frame, a pair of rails on the sides of said frame, means for forming the lower side of a tile, a manually operable smoothing bar, blocks dowelled to said bar slidable on said rails, means for adjusting said blocks 80 relative to said bar, and guide lugs on said blocks engaging the sides of said rails.

2. A tile making machine comprising a frame, a pair of spaced rails on said frame, means in said frame for forming a tile, a 85 tamping bar slidable on said rails, a smoothing bar removably engaging said rails, blocks dowelled to said bar, and a screw intermediate said dowels for adjusting said smoothing bar relative to said rails by raising or lowering the same, said blocks having guide members contacting with the sides of said rails.

This specification signed and witnessed this 28th day of April, 1922.

EMIL R. JAHNA.
